UNITED STATES PATENT OFFICE.

CHARLES L. CREAR, OF NEW YORK, N. Y.

DESIGN FOR A THERMOMETER-HOLDER.

SPECIFICATION forming part of Design No. 14,091, dated July 17, 1883.

Application filed June 5, 1883. Term of patent 7 years.

To all whom it may concern:

Be it known that I, CHARLES L. CREAR, of the city, county, and State of New York, have invented and produced a new and original 5 Design for Thermometer Supports or Holders, of which the following is a specification, reference being had to the accompanying drawings, forming part hereof.

Figure 1 shows my newly-designed thermometer-support as adapted to be suspended by its ring from a hook or otherwise. Fig. 2 shows the device adapted to rest on a table, for example, as an ornament.

The leading feature of my design consists 15 in making the thermometer-support in the form of a ship's anchor. It will be seen that all the parts of a ship's anchor are present—namely, the ring A, the stock B, the shank C, the arms D, and the flukes E. The shank is 20 made with a flat side, to which are secured the thermometer and scale by rivets or any suitable means. In Fig. 1 the stock B is shown

arranged in the same plane as the arms D, this arrangement being preferable when the device is to be hung up by the ring A. In Fig. 25 2 the stock is arranged at right angles to the arms D, as in an actual anchor, rendering the device suitable in form for a table ornament. I prefer to make the anchor of metal and ornament it by plating.

30 I claim—

1. The design for a thermometer support or holder herein shown and described, consisting of a ship's anchor having the stock in the same plane as the arms.

35 2. The design for a thermometer support or holder herein shown and described, consisting of a ship's anchor having the stock arranged in a plane at right angles to the plane of the arms.

CHAS. L. CREAR.
